Primary Examiner — Elizabeth J Oswecki(74) *Attorney, Agent, or Firm* — Sughrue Mion, PLLC(57) **CLAIM**

The ornamental design for a helmet shield, as shown and described.

DESCRIPTION

FIG. 1 is a front view of a helmet shield showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a cross-sectional view taken along line 7-7 of FIG. 1;

FIG. 8 is a cross-sectional view taken along line 8-8 of FIG. 1;

FIG. 9 is a partial enlarged view taken along line 9-9 of FIG. 7;

FIG. 10 is a partial enlarged view taken along line 10-10 of FIG. 8;

FIG. 11 is a perspective view of FIG. 1; and,

FIG. 12 is another perspective view thereof attached to a helmet shown in a used condition.

The broken lines shown in the drawings represent portions of the helmet shield that form no part of the claimed design.
